United States Patent Office

Des. 185,858

Patented Aug. 11, 1959

185,858

STORAGE BATTERY CONTAINER

Van Nelson, Monterey Park, Calif., assignor to Stauffer Chemical Company, a corporation of Delaware

Application January 8, 1959, Serial No. 54,084

Term of patent 14 years

(Cl. D26—6)

Fig. 1

Fig. 3

Figures 1 and 2 are side elevations of opposite sides of a storage battery container showing my new design; and Figure 3 is a view of one of the two similar ends of the storage battery container.

The top and bottom of the container are conventional. I claim:

The ornamental design for a storage battery container, as shown and described.
